UNITED STATES PATENT OFFICE.

GEORGE W. POLK AND GEORGE W. BURKE, JR., OF DAYTON, OHIO.

FIRE-EXTINGUISHING APPARATUS.

Application filed March 29, 1923. Serial No. 628,478.

This invention relates to fire extinguishing apparatus, the object in view being to provide a portable fire extinguisher of large capacity, especially designed for use in air-
5 plane and aircraft hangars, where compactness and size are important features, in view of the fact that it is necessary to carry or transport the fire extinguishers under the wings of airplanes.

10 A further object of the invention is to provide a fire extinguisher containing fire extinguishing fluid or liquid, a pressure means for expelling the same from a suitable container, and a single valve for throwing the device into full operation. The fire extinguisher is illustrated as of the wall type, as fire extinguishers for the purpose above referred to are usually hung at various places around the walls of an airplane hangar
15 20 where they will be convenient at all times.

With the above and other objects in view, the invention consists in the novel construction, combination and arrangement herein described, shown and claimed.

25 In the accompanying drawings.

Figure 1 is a side elevation of the fire extinguisher.

Figure 2 is a vertical diametrical section through the same, showing certain parts in elevation.

30 The improved fire extinguisher embodies a container 5, preferably of hollow, cylindrical formation and having fitted to one end thereof a removable cap 6 to give access 35 to the interior of the container. A bail shaped handle 7 is fitted to the container 5, enabling the same to be carried readily or hung upon a wall or other support.

Within the lower end of the container
40 45 there is a bottle-like holder 8 containing suitable fire extinguishing fluid or liquid such as carbon tetrachloride, said holder being provided at its lower end with a filler cap 9 tightly screwed or otherwise fitted thereon and also communicating at its lower end with a discharge pipe 10 which extends longitudinally within the container 5 to a point near the upper end thereof, where it is extended laterally through the wall of the
50 container leaving a nipple end 11 to which a flexible hose 12 is applied, the hose 12 having at its free end a suitable nozzle 13.

In the upper portion of the container 1 there is another bottle-like holder 14 containing any suitable gas under compression 55 such as carbonic acid gas. A pipe connection 15 extends from the holder 14 to the holder 8 for carrying the pressure from one to the other and a single manually operable valve 16 controls the pipe connection 15. 60 The valve 16 is provided on the outer end thereof, exterior of the container 1 with a hand wheel 17 or any other suitable operating device.

In operating the fire extinguisher, it is 65 only necessary to open the valve 16 by means of the handle or operating device 17. Immediately thereupon the pressure in the holder 14 is liberated and passes to the interior of the holder 8, thereby forcing the 70 fire extinguishing fluid or liquid therefrom through the pipe 10 and the hose 12, and outward through the distributing nozzle 13. Usually the fire extinguisher is transported from place to place upon a wheeled truck 75 and therefore compactness and size are important features as it is necessary to carry the fire extinguisher under the wings of airplanes. Upon arriving at the point where the fire occurs, it is only necessary to direct 80 the hose 13 toward the fire and set the fire extinguisher into full operation by turning the handle or wheel 17.

We claim:

A portable fire extinguisher comprising a 85 container, a separable fire extinguishing fluid chamber mounted in said container adjacent one end thereof, a separable gas chamber mounted in said container and adjacent the opposite end thereof, means connecting 90 said chambers wholly interior of said container, a discharge pipe extending from the bottom of said fluid chamber to a point adjacent the top of said container and through the side wall thereof, and unitary means 95 operable exteriorly of said container to control the flow of gas through said connecting means and into said fluid chamber to expel the fluid from said chamber through said discharge pipe.

100 In testimony whereof we affix our signatures.

GEORGE W. POLK.

GEORGE W. BURKE, JR.
